UNITED STATES PATENT OFFICE.

JOHN BRUFF MURRAY, OF ADRIAN, OHIO, ASSIGNOR, BY DIRECT AND MESNE ASSIGNMENTS, TO JOSEPH E. MYERS, OF CAREY, OHIO.

BURIAL-VAULT.

950,112.

Specification of Letters Patent. Patented Feb. 22, 1910.

Application filed April 1, 1909. Serial No. 487,369.

To all whom it may concern:

Be it known that I, JOHN B. MURRAY, a citizen of the United States, residing at Adrian, in the county of Seneca and State 5 of Ohio, have invented certain new and useful Improvements in Burial-Vaults, of which the following is a specification.

My invention relates to improvements in burial-vaults formed of concrete, cement, or 10 other plastic material, the primary object of the invention being to provide a generally improved burial-vault of this class which, by reason of the reinforcement of its walls and the particular arrangement and configuration 15 of the latter will be better adapted to its intended purposes than any other vault of the same class with which I am acquainted.

The invention relates more particularly to the means and method of reinforcing the 20 rectangular main body portion and lid or cover of the vault whereby a vault of generally improved reinforced construction is provided.

Another object of the invention is to provide a "self-sealing" lid or cover of improved construction provided about its peripheral or marginal edges with a rectangular shaped depending flange, and a case body provided with a peripheral outwardly-projecting lid-supporting portion or ledge 30 having a rectangular shaped seal-receiving groove adapted to receive and contain said depending flange of the lid or cover when the latter is placed in position.

With the above mentioned objects in view, the invention consists in the novel construction, arrangement, and combination of parts, hereinafter described, illustrated in one of its embodiments in the accompanying drawings, and particularly pointed out in the appended claims.

Referring to the drawings, forming a part of this specification, Figure 1, is a perspective view of a burial-vault constructed in accordance with this invention. Fig. 2, is a cross sectional view of the same with the lid or cover in an elevated position. Fig. 3, is a detail perspective view of the improved reinforcing frame for reinforcing the lid or cover. Fig. 4, is a detail perspective view of the improved reinforcing frame for reinforcing the vault or case body.

Similar numerals of reference designate like parts throughout all the figures of the 55 drawings.

The improved vault comprises a rectangular shaped main body portion consisting of side and end walls 1, and 2, preferably paneled as shown and reinforced or strengthened by means of peripheral or marginal strengthening panels 3. The side walls may be further strengthened by means of an upright intermediate panel 4, and diagonally disposed panels 5. The side and end walls of the vault or case body are 60 formed or built up of cement or concrete in a well known manner and have embedded therein a rectangular shaped reinforcing wire frame which will now be described.

As shown most clearly in Fig. 4, of the 70 drawings the reinforcing frame embedded in the case body comprises a plurality of horizontally-extending rectangular members 6, and a plurality of wall reinforcing members consisting of horizontally-extending intersecting bottom portions 7, terminating in vertically-extending side and end wall reinforcing portions 8, intersecting said rectangular members 6, all of said reinforcing members being secured by a welding at the 80 intersecting portions thereof as at 9, said welding being preferably formed by the electric welding process. By reason of the relative disposition and arrangement of the members 6, 7, and 8, and the manner of securing the intersecting portions thereof together a generally improved reinforcing frame of great strength and rigidity is produced. The reinforcing frame for reinforcing the lid or cover comprises a plurality of 85 longitudinally and transversely extending intersecting members 10, and 11, respectively, said transversely extending members being preferably arched as shown and the intersecting portions of said members 10, and 11, being welded together in a manner similar to the intersecting portions of the reinforcing frame for the case body above described. The reinforcing frame for the lid or cover is provided at its sides with 90 wire loop eyes 12, adapted to project above the lid or cover 13, as shown most clearly in Fig. 1, of the drawings.

The bottom of the vault or case body is provided with a centrally located raised rectangular shaped panel portion 14, having its marginal edges horizontally-spaced from the side and end walls of the case body (see Fig. 2,) and is adapted to form a resting or bearing plate for the casket and enables the 110

straps surrounding the latter to be readily removed when the casket is placed in the vault. The side and end walls of the vault body terminate at their upper portions in a peripheral outwardly-projecting lid-supporting portion or ledge 15 of substantially triangular shape in cross section and providing a broad upper bearing surface and containing a rectangular shaped seal-receiving groove 16 (see Fig. 2) said seal receiving groove being preferably provided with an inverted V-shaped projection 16^a. The groove 16, is adapted to receive the plastic cement or sealing material so as to hermetically seal the lid or cover when the latter is placed in position as hereinafter described. The seal receiving groove 16, is horizontally-spaced from the outer peripheral edge of the lid supporting portion 15, thus providing an outer lid supporting ledge 15^a, to be covered by an overhanging ledge of the lid or cover when the latter is placed in position thus protecting the plastic seal from earth and foreign matter during the filling of the grave.

The lid or cover 13, is provided with a depending flange 17, adapted to take into and normally rest within the seal receiving groove 16, said depending flange 17, being similar in shape and contour to the seal receiving groove 16, and being provided with an inverted V-shaped groove 17^a; adapted to receive and take over the similarly shaped projection 16^a, when the lid or cover is placed in position in the sealing operation. The depending flange 17, is horizontally spaced from the outer peripheral edge of the lid or cover thus providing an overhanging ledge 18, adapted to register with and take

over the outer lid supporting ledge 15^a, of the case body when the lid or cover is placed in position as shown most clearly in Figs. 1, and 2, of the drawings.

From the foregoing description, taken in connection with the accompanying drawings, the operation and advantages of my invention will be readily understood.

Having thus described my invention, what I claim and desire to secure by Letters Patent is—

A burial vault, comprising a rectangular body provided with a peripheral outwardly-projecting lid-supporting ledge, of triangular shape in cross section, about the upper marginal edges of its side and end walls, said ledge having a broad upper bearing surface and provided with a rectangular shaped seal-receiving groove surrounded by an outer lid-supporting bearing portion, and a cover provided with an overhanging ledge adapted to register with and cover said outer lid-supporting bearing portion and having a rectangular shaped depending flange extending from the inner marginal edges of said overhanging ledge and normally seated in said seal-receiving groove, said groove being provided in its base portion with an inverted V-shaped projection and said depending flange being provided with a similarly shaped groove taking over said projection after the initial insertion of said depending flange in said seal-receiving groove.

In testimony whereof I have affixed my signature, in presence of two witnesses.

JOHN BRUFF MURRAY.
